INVENTOR:

Sigvart C.O. Berg,

BY
F. G. Fischer,
ATTORNEY.

UNITED STATES PATENT OFFICE.

SIGVART C. O. BERG, OF KANSAS CITY, MISSOURI.

SWITCH-LOCK.

1,256,767.

Specification of Letters Patent. Patented Feb. 19, 1918.

Application filed October 30, 1916. Serial No. 128,460.

To all whom it may concern:

Be it known that I, SIGVART C. O. BERG, a citizen of the United States, residing at Kansas City, in the county of Jackson and State of Missouri, have invented certain new and useful Improvements in Switch-Locks, of which the following is a specification.

My invention relates to switch locks and while susceptible to general use is adapted 10 more particularly for locking in off or open position the switches employed on Ford cars for controlling the ignition system.

Among the important features of the invention may be mentioned a lock which can- 15 not be easily picked, and one which, when locked, cannot be removed from the switch to gain access thereto for the purpose of closing the ignition system.

Other objects of the invention will herein- 20 after appear, and in order that said invention may be fully understood, reference will now be made to the accompanying drawing, in which:

Figure 1 is a front elevation of the lock 25 mounted upon the customary switch.

Fig. 2 is a rear elevation of the lock re- 30 moved from the switch.

Fig. 3 is a vertical section of the lock on line III—III of Fig. 1.

Fig. 4 is a detail perspective of a ward 35 constituting a portion of the lock.

Fig. 5 is a detail perspective of a wing 40 constituting a portion of the ward.

A designates the usual switch employed 45 for opening and closing the ignition system on the Ford car.

1 designates the lock case provided at its rear side with a plurality of eyes 2 for the 50 reception of screws B, whereby said case is 40 removably secured to the face of the switch A. Access with a screw driver is had to the 55 screw heads when the same are bearing against the eyes 2, through holes 3 arranged in alinement with the screw holes in said 45 eyes 2.

5 designates a barrel rotatably mounted 50 in the case 1 near the central portion thereof and provided at its inner end with two dia- 55 metrically opposed lugs 6, adapted to enter the grooved portions C of the rotary contact of the switch A.

The barrel 5 is reliably held in the case 1 60 by a front marginal flange 7 and a ward 8, which latter is removably secured upon the 65 rear portion of the barrel by suitable means, such as screws 9. The barrel 5 has a cen-

trally-disposed key-hole 10 to receive the bit of a key 11, whereby said barrel can be rotated to locked and unlocked positions.

When the barrel is rotated to locked po- 60 sition it is secured in such position by a plu- 65 rality of tumblers 12, slidably-mounted in bores 13 in the case and bores 14 in the barrel 5. The remote ends of the bores 13 are closed by plugs 15, springs 16 being first in- 65 serted in said bores to yieldingly-force the tumblers 12 toward the center of the key- 70 hole 10. Movement of the tumblers 12 to- 75 ward the center of the key-hole is limited by their pointed terminals contacting the re- 70 duced ends of the bores 14.

Each tumbler 12 consists of two pieces, one of which is contacted by the key 11, as disclosed by Fig. 3, to unlock the tumbler, the other being adapted to be forced by its 75 respective spring 16 across the joint between the barrel 5 and the case 1, to lock said barrel from rotation until unlocked by the in- 80 sertion of the key 11, as aforementioned.

Returning to the ward 8, the purpose of 80 which is to assist in holding the barrel 5 in position in the case 1 and cover the heads of the screws B when the barrel is locked, it will be noted by referring to Figs. 2, 4 and 5, that said ward has a plurality of fixed 85 wings 18 projecting therefrom and a mov- 90 able wing 19. Said movable wing 19 is piv- 95 oted at its upper end upon a stud 20 pro- 100 jecting rearwardly from the case 1, and said wing has a longitudinal slot 21 to receive a finger 22 projecting forwardly from the lower portion of the ward 8.

With the parts constructed and arranged as shown in the present instance, the barrel 5 is held from rotation by the tumblers 12, 95 and in turn holds the switch A in off po- 100 sition. At the same time the holes 3 are cov- 105 ered by the wings 18 and 19, so that access cannot be had to the screws B for the pur- 110 pose of removing the lock from the switch. Upon the insertion of a proper key, as disclosed by Fig. 3, the tumblers 12 are forced inwardly until their joints register with the joint between the case 1 and the barrel 5, whereupon the latter can be rotated in one direction by the key 11 to throw the switch first into contact with the battery side and after the motor has been started, to the magneto side. The rotation of the barrel 5 rotates the ward 8 and uncovers the holes 3, so that the lock can be removed from the switch for repairs if necessary.

From the foregoing description, it is apparent that I have produced a lock whereby an unauthorized person unprovided with a proper key is prevented from stealing a car equipped with said lock, and while I have shown and described the preferred form of my invention, I reserve the right to make such changes in the construction, combination and arrangement of parts as properly fall within the spirit and scope of the claims.

Having thus described my invention, what I claim and desire to secure by Letters Patent, is:

15. 1. In combination with a casing and a mechanism therein, a lock consisting of a case having screw receiving means in its rear portion so that it can be secured by screws to said casing, a barrel journaled in said case and adapted to control the mechanism, a ward secured to said barrel to rotate therewith and provided with integral wings to cover a number of the screw heads when the barrel is in locked position, a pivoted wing to cover one of the screw heads,
- 20
- 25

means on the ward for actuating said pivoted wing, and tumblers for locking said barrel.

2. In combination with a casing and a mechanism therein, a lock consisting of a case having screw-receiving means in its rear portion so that it can be secured by screws to said casing, a barrel journaled in said case and adapted to control the mechanism, a ward secured to said barrel to rotate therewith and provided with integral wings to cover a number of the screw heads when the barrel is in locked position, a slotted pivoted wing to cover one of the screw heads, a finger projecting from the ward through the slotted portion of the pivoted wing to actuate the same, and means for locking the barrel.

In testimony whereof I affix my signature, in the presence of two witnesses.

SIGVART C. O. BERG.
